MOUNTING CONSTRUCTION FOR CHALK BOARDS, CORKBOARDS AND LIKE PANELS

Joseph N. Maertzig, Jr., 961 Granite St.,
Philadelphia 24, Pa.

Filed Dec. 23, 1960, Ser. No. 78,128
4 Claims. (Cl. 189—88)

This invention relates generally to improvements in the mounting of chalk board, corkboard and similar panels on a building wall or other suitable support structure.

It is one object of the present invention to provide a mounting construction for chalk board, corkboard and like panels which may be quickly and easily installed, without special preparation of the support structure, and without the use of special tools or exercise of special skills.

It is a further object of the present invention to provide a panel-mounting construction of the type described which includes elements for mounting adjacent panels, as well as a single panel, and for retaining trim in position both between adjacent panels and bounding a single panel.

It is a further object of the present invention to provide a panel-mounting construction having the advantageous characteristics mentioned in the preceding paragraphs which is extremely simple in structure, staunch, durable and reliable in use, and which can be economically manufactured for sale at a reasonable price.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

FIGURE 1 is an elevational view showing a chalk board and corkboard mounted upon a wall, partly broken away for conservation of drawing space;

FIGURE 2 is a sectional view, taken substantially along the line 2—2 of FIGURE 1, somewhat enlarged for clarity of understanding;

FIGURE 3 is a perspective view showing one element of the present invention apart from the assembly of FIGURES 1 and 2;

FIGURE 4 is a top view of the element shown in FIGURE 3;

FIGURE 5 is an elevational view of the element shown in FIGURE 3; and

FIGURE 6 is a perspective view showing another element of the present invention apart from the operative assembly.

Referring now more particularly to the drawings, and specifically to FIGURES 1 and 2 thereof, a supporting structure, base or wall is there designated 10, and a panel assembly, generally designated 12 is mounted on the wall. The panel assembly may vary as desired, and for purposes of illustration and without limiting intent, is shown as including a generally rectangular corkboard or panel 13 arranged in proximate facing relation with the supporting wall 10, and a chalk board or panel 14 located in substantially coplanar, edge-to-edge spaced relation with respect to the corkboard. An intermediate molding or trim strip 15 extends between the panels 13 and 14, while a bounding or edge trim or molding 16 extends about the combined area of both the panels 13 and 14. Further, concealed beneath the trim 15 and 16 in FIGURE 1, there are secured to the supporting structure or wall 10 a plurality of mounting elements or clips 18 located

2

between and engaging both the panels 13 and 14, and a plurality of mounting elements or clips 19 secured to the supporting wall about and in supporting engagement with the outer edge regions or margins of both the panels 13 and 14. Thus, the supporting elements or clips 18 are located intermediate or between adjacent panels 13 and 14, while the supporting elements or clips 19 are located about the margins of the panels.

In FIGURES 3, 4 and 5 are shown, in greater detail, a mounting element or clip 18 of somewhat channel-like configuration. The mounting element or clip 18 includes a generally flat, substantially rectangular back portion 20 adapted to be secured fast in facing engagement with a supporting structure or base, such as the wall 10. For receiving securing fasteners or screws, as at 22, one or more through apertures or holes 23 may be provided in the back portion 20.

Along opposite sides of the back portion 20 are forwardly extending or outstanding walls generally designated 25 and 26, respectively. Further, the outstanding side wall 25 is constituted of a pair of side-wall sections 27 and 28, each of approximately rectangular configuration and extending from the adjacent side edge of back portion 20 alongside each other. More specifically, the side-wall section 27 extends forward from and approximately normal to the back portion 20, along one side edge thereof proximate to the end edge 29, while the side-wall section 28 extends obliquely forward and outward laterally away from one side edge of the back portion adjacent to the end edge 30 of the back portion. As best seen in FIGURES 2 and 4, the side-wall section 27 extends forward further than the side-wall section 28, or conversely, the side-wall section 28 terminates in the forward direction short of the side-wall section 27. On the distal region of the side-wall section 27, extending generally normal thereto and laterally outward therefrom is provided a generally rectangular resilient extension or leaf 31, which has its outer end region bent to define an obliquely forwardly and laterally outwardly extending formation 32. Extending laterally outward from the distal end of wall section 28, and resiliently carried thereby, is a generally rectangular portion or leaf 33. The leaf 33 is disposed in a plane generally parallel to and spaced between the planes of back portion 20 and leaf 31. Thus, the leaves 31 and 33 are offset from each other in the direction normal to their planes and to the plane of the back portion 20; and further, the leaves 31 and 33 are offset from each other longitudinally of the back portion 20 as in the direction extending between the back-portion end edges 29 and 30.

The side wall 26 may be considered as constituted of a pair of outstanding wall sections 37 and 38 extending from the other longitudinal or side edge of back portion 20, with the wall section 37 adjacent to the back-portion end 30, the wall section 38 adjacent to the back-portion end 29, and the wall sections alongside of each other. The wall section 37 is similar to the wall section 27, extending forward from and generally normal to the back portion 20, while the wall section 38 extends obliquely forward and laterally outward from the back portion terminating short of the wall section 37 in the forward direction. A generally rectangular resilient extension or leaf 41 projects laterally outward from the distal end of wall section 37, substantially normal thereto. The outer end region of the leaf 41 is bent or curved forwardly and laterally inwardly to define a curled formation 42. Extending laterally outward from the distal end of the wall section 38 is a generally rectangular portion or leaf 43 disposed in a plane parallel to and spaced between the planes of the back portion 20 and leaf 41.

Thus, the wall sections 37 and 38 are similar, respectively, to the wall sections 27 and 28, while the leaves 41

and 43 are respectively similar to the leaves 31 and 33. However, the distal end formation 42 of the leaf 41 differs from the distal-end formation 32 of leaf 31 in that the former presents a smooth, arcuately convex laterally outwardly facing surface. Further, it will be observed that the oblique wall section 28 is located laterally opposite to the normal wall section 37, while the normal wall section 27 is located laterally opposite the oblique wall section 38.

In use, as seen in FIGURES 1 and 2, a plurality of the mounting elements or clips 18 are secured fast, as by fasteners 22, in spaced relation to a supporting structure or wall 10, with the back portions 20 of the several mounting elements in end-to-end, spaced aligned relation. In this condition, one wall panel 13 may have its upper edge region snugly engaged between and resiliently embraced by the leaves 41 and 43. That is, the leaves 41 and 43 firmly frictionally engage opposite faces of the panel 13 adjacent to the upper edge thereof. The upper panel 14 may have its lower margin entering between and engaged by the resilient leaves 31 and 33 to be frictionally retained thereby.

The mounting elements or clips 19 are best seen in FIGURE 6 as including a generally rectangular, substantially flat back portion 50 having opposite ends or end edges 51 and 52 and provided with one or more apertures or holes 53 for receiving securing fasteners, as at 54 in FIGURE 2. Along one longitudinal or side edge of the back portion 50 is an outstanding wall, generally designated 55, which may be constituted of a pair of side-by-side wall sections 57 and 58. The wall section 57 may be generally rectangular and extend forward from one side edge of the back portion 50, substantially normal thereto, being provided on its distal end with a laterally outwardly projecting, generally rectangular, resilient extension or leaf 61. The laterally outer end region 62 of the leaf 61 is bent to define an obliquely forwardly and laterally outwardly extending formation. The leaf 61 is substantially normal to the wall section 57, so as to be parallel to and spaced from the plane of back portion 50.

The wall section 58 is generally rectangular and extends obliquely forwardly and laterally outward from the back portion 50 alongside of the wall section 57 and terminates forwardly short of the wall section 57. Extending laterally outward from the distal end of wall section 58 is a generally rectangular extension or leaf 63 located in a plane parallel to and spaced between the planes of leaf 61 and back portion 52. The leaf 63 is thus resiliently carried by the wall section 58, being offset rearwardly from the plane of leaf 61 and offset longitudinally of the back portion 50 from the leaf 61. Thus, it will be appreciated that the wall 55 and leaves 61 and 63 are similar to the wall 25 and leaves 31 and 33 of mounting element 18.

Carried by the back portion 50, on the side edge thereof opposite to the wall 55, is a forwardly curled formation 65.

In the operative assembly of FIGURE 2, the mounting element or clip 19 is secured by a fastener 54 with its back portion 50 in facing engagement with the supporting structure or wall 10. The upper marginal region of panel 14 engages between the resilient leaves 61 and 63, the leaves serving to firmly frictionally engage opposite faces of the panel 14.

The intermediate trim piece 15 is of an elongate, hollow or channellike configuration, including an outer or forward wall 67, and rearwardly extending side walls or flanges 68 and 69. The flanges 68 and 69 have their edge portions 70 and 71, respectively, turned or bent obliquely inward. By this construction, it is only necessary to engage the inturned flange edge portion 71 behind the out-turned leaf end portion 32 and forcibly snap engage the flange edge portion 70 over the formation 42 to positively retain the trim in position.

The marginal trim 16 is of similar hollow, channellike

configuration including a front or outer wall 72, and longitudinal side walls 73 and 74. The edge regions of the side walls are bent inward, as at 75 and 76, respectively. The marginal trim may be assembled by engaging the inturned wall edge portion 75 behind the formation 62, and forcibly snap engaging the side-wall edge portion 76 over the formation 65. It will be observed that the marginal trim 16 has one side wall 74 of greater depth or width than the other side wall 63, for extension of the wider side wall to the support structure or wall 10.

While the clips or mounting elements 18 and 19 of the present invention may each preferably be integrally fabricated of resilient sheet metal, as by simple and inexpensive stamping operation, it is, of course, understood that the clips of the instant invention may be manufactured otherwise, is desired, and fabricated of any suitable material.

Thus, it will be appreciated that the clips or mounting elements of the present invention are capable of extremely economical manufacture, as well as extremely rapid and easy installation and assembly with chalk boards, corkboards and the like panels. Further, it will be observed that the intermediate clip 18, by the relative arrangement of leaves 31 and 33 in respective laterally opposed relation with leaves 43 and 44 affords the unique, firm frictional embracing engagement with both adjacent edge-to-edge spaced panels 13 and 14, and wherein a reaction torque is imparted to each adjacent pair of leaves, which reaction torques are in opposite angular directions to cancel each other. This serves to prevent undue stress, strain and vibration being transmitted to the mounting elements for substantially indefinite durability and firm securement to their panel elements and supporting structure.

From the foregoing it is seen that the present invention provides a mounting construction for corkboard, chalk board and like panels which fully accomplishes its intended objects and is well-adapted to meet practical conditions of manufacture and use.

While the clip 18 has been described as for use between or intermediate adjacent panels, if desired the clip 18 may be employed peripherally about one or more panels for retaining peripheral trim. Such trim may be similar to that shown at 16, but provided with an inwardly upset portion of the wall 74 spaced from its edge for engagement with the curled portion 42 of the clip. It is, of course, also appreciated that the trim may be provided with formations defining a chalk rail, or the like, as desired, without departing from the instant invention.

Although the present invention has been described in some detail by way of illustration and example for purposes of clarity of understanding, it is understood that certain changes and modifications may be made within the spirit of the invention and scope of the appended claims.

What is claimed is:

1. A mounting construction for chalk boards, corkboards and like panels comprising a clip adapted to be mounted at an edge of a panel, said clip including a platelike anchoring portion, a pair of resilient leaves extending in one direction from said anchoring portion and offset from each other in two directions both substantially normal to said one direction, said leaves being adapted to receive therebetween and resiliently engage opposite sides of a panel, a first securing formation on the distal region of one of said leaves, a second securing formation carried by said anchoring portion remote from said leaves, said first and second securing formations being adapted for securing engagement in a hollow trim to retain the latter in position, and a second pair of resilient leaves extending in the opposite direction from said anchoring portion as said first-mentioned pair of leaves and offset from each other in said two directions both substantially normal to said one and opposite directions, said second pair of leaves being adapted to receive therebetween and resiliently engage opposite sides

of a second panel, said second securing formation being carried by one of said second pair of leaves at the distal region thereof, and said second pair of leaves being offset oppositely to said first-mentioned pair of leaves in one of said two normal directions so that said first and second pairs of leaves impart opposite and counteracting reaction torques from said panels to said anchoring portion.

2. A mounting construction for chalk boards, cork-boards and like panels comprising a clip adapted to be mounted at an edge of a panel, said clip including a platelike back portion, a first wall section extending forward from one side of said back portion, a second wall section extending forward from said one side of said back portion adjacent to and terminating short of said first wall section, a resilient leaf extending from the distal end of each wall section laterally outward from said back portion, said leaves being offset from each other and adapted to receive therebetween and resiliently engage opposite sides of a panel, a first securing formation on the distal region of the leaf of said first wall section, a pair of additional wall sections extending forward from said other side of said back portion, an additional resilient leaf extending from each of said additional wall sections laterally outward away from said back portion, said additional leaves being offset from each other and adapted to receive therebetween and resiliently engage opposite sides of a second panel, and a second securing formation carried by the distal region of one of said additional leaves, said first-mentioned and additional leaves being diagonally positioned with respect to each other to effectively nullify forces imparted to said back portion, said first and second securing formations being adapted for engagement in a hollow trim for retaining the latter in position.

3. A mounting construction for chalk boards, cork-boards and like panels comprising a clip adapted to be mounted at an edge of a panel, said clip including a platelike back portion, a first wall section extending forward from one side of said back portion, a second wall section extending forward from said one side of said back portion adjacent to and terminating short of said first wall section, a resilient leaf extending from the distal end of each wall section laterally outward from said back portion, said leaves being offset from each other and adapted to receive therebetween and resiliently engage opposite sides of a panel, a first securing formation on the distal region of the leaf of said first wall section, a second securing formation carried by said back portion remote from said leaves, said first and second securing formations being adapted for engagement in a hollow trim for retaining the latter in position, a pair of additional wall sections extending forward from the other side of said back portion, and an additional resilient leaf extending from each of said additional wall sections lat-

erally outward away from said back portion, said additional leaves being offset from each other and adapted to receive therebetween and resiliently engage opposite sides of a second panel, and said second securing formation being carried by the distal region of one of said additional leaves, the leaves of said first and second wall sections being offset to impart a reaction torque to said back section in one direction, and said additional leaves being offset to impart a reaction torque to said back portion in the opposite direction.

4. A mounting construction for chalk boards, cork-boards and like panels comprising a clip adapted to be mounted at an edge of a panel, said clip including a platelike back portion, a first wall section extending forward from one side of said back portion, a second wall section extending forward from said one side of said back portion adjacent to and terminating short of said first wall section, a resilient leaf extending from the distal end of each wall section laterally outward from said back portion, said leaves being offset from each other and adapted to receive therebetween and resiliently engage opposite sides of a panel, a first securing formation on the distal region of the leaf of said first wall section, a second securing formation carried by said back portion remote from said leaves, said first and second securing formations being adapted for engagement in a hollow trim for retaining the latter in position, a pair of additional wall sections extending forward from the other side of said back portion, and an additional resilient leaf extending from each of said additional wall sections laterally outward away from said back portion, said additional leaves being offset from each other and adapted to receive therebetween and resiliently engage opposite sides of a second panel, and said second securing formation being carried by the distal region of one of said additional leaves, the leaves of said additional pair being located respectively laterally opposite to the leaves of said first and second wall sections with the forwardmost leaf of each pair laterally opposite to the rearwardmost leaf of the other pair.
